YARN CARRIER WITH TAKEUP DEVICE
FOR HOSIERY MACHINES

Josef S. Karl, Athens, Ga.

Application July 21, 1950, Serial No. 175,119

10 Claims. (Cl. 66—126)

1

In a full fashioned hosiery knitting machine an important factor in the knitting of an even fabric is the correct tension on the yarn as it travels from the cone to the knitting head. If there is not enough tension on the yarn as it is being taken from the cone during the knitting course, slightly more yarn than is necessary will be thrown from the cone. The result is loose, irregular knitting, especially near the selvedges of the fabric. The yarn, as it goes from the cone to the yarn carrier, passes through several devices that take up the slack in the yarn and give it the necessary tension for the making of a perfect fabric. One of these devices is known as the ring tension motion. It consists of a brass or plastic ring which slides vertically on a bent wire ring holder.

However, although the tension exerted by the rings as well as other devices of the same character will exert a continual drag necessary to an even distribution of the yarn, additional tension is needed when the carrier comes to the end of its course and the needles form the loops. At this instant, and when the narrowing machine is transferring the loops to their new position on the needles, a "snapper" is used to provide the necessary backward pull on the thread in order to form and maintain a firm selvedge. If no backward pull were exerted on the thread at these times, the yarn already issued from the carrier tube would be loose due to the inward movement of the needles while forming the loops or the upward movement of the fabric imparted by the narrowing machine, thus making a sleasy, loose selvedge. If the snappers are slightly loose on the snapper shaft their constant vibration will cause uneven tension on the yarn as it is drawn through and will result in the formation of loose loops at the selvedge of the fabric, as well as distorted loops throughout the complete course. If the snapper springs are not all adjusted to the same, correct tension, or if there are any split or grooved porcelains on the snappers, uneven and poorly formed selvedges result. Since the snapper springs are adjusted by bending them with the fingers, there can be no uniformity of tension among the carriers. Due to the differing elasticities of yarns and the distance from the snappers to the carrier tubes, further adjustments may be necessary when changing yarns.

I propose to eliminate such difficulties by substituting for the snapper motion a novel form of takeup located on the carrier itself, close to the knitting action, thus eliminating the problem of yarn stretch, and of a character that produces automatically a predetermined and equal backward pull on the yarn whenever the carrier comes to rest.

Since my novel takeup device can obviate any necessity for snappers, it can result in considerable savings in the manufacture of full fash-

2

ioned hosiery machines. Many heavy castings as well as several expensively machined cams need not be made and shipped, assembled and adjusted, thus resulting in saving several hundreds of dollars on each machine. These takeup devices may in fact be made in the form of attachments readily attachable to existing machines in such manner that a minimum of time would be lost in converting the machine to my system of takeup device. In addition, if any difficulty is encountered during knitting, there would be but a few seconds' time loss to the knitter in substituting a new takeup device for the original, and there is not the necessity of adjusting to correct tension as is needed in the use of snappers.

Fig. 1 is a front view illustrating one form of my invention showing it snapped on a conventional carrier assembly.

Fig. 2 is a side view showing the positions of the takeup devices while the carrier is in motion.

Fig. 3 shows one form of blank used in manufacturing the device.

Fig. 4 shows a partial side view and section enlarged to show the takeup devices in their operating position.

Fig. 5 is an enlarged side view of one of the takeup devices showing one form of stop used to prevent the device flying out too far.

Fig. 6 is an enlarged section taken on the line 6—6 of Fig. 1 showing how the device is secured to the carrier.

The carrier assembly consists of the holder plate 10 to which the arm 11 is secured by a cross strap 12 and bolts 13, 13. This assembly is secured to the carrier rod 14 in the usual manner by bolts 15, 15.

The assembly has an introductory eyelet or guide 16 and a discharge tube 17. The yarn or thread 18 passes through the guide 16, over the guide pin or roller 19, under the guide pin or roller 20, over the guide pin or roller 21, under the guide pin or roller 22, over the guide pin or roller 23, over the guide pin or roller 24, and is guided through the groove 25 to the discharge tube 17.

The guides 19 and 21 are carried by the supports 26 and 28 respectively. The guides 20 and 22 are supported by arms 27 and 29 respectively, which are hinged on the ends of the guide pins 19 and 21 respectively.

The guide pins or rollers 20 and 22 are thus supported so as to swing freely on the pivots 19 and 21. It will be understood, of course, that each carrier assembly is mounted at an incline so that the guides 20 and 22 are moved by gravity to press against the yarn or thread.

Guide 23 is carried by a support 30. Each of the supports 26 and 28 is provided with a suitable stop 31 to limit the outward throw of its swinging guide.

In its preferred form, the invention contem-

plates mounting all of the guides except the tubular outlet 17 upon a common support which may be in the form of a sheet metal strip 32 detachably mounted on the carrier assembly, as for instance, by means of a cross piece 33 having a hook 34 for engaging one edge of the holder plate 10, and a latch piece 35 for snapping over the opposite edge.

The support 26 may be formed by stamping out portions 26' from the cross piece 33. An additional clamp-on device 36 may carry the support 30 which is formed by stamping a piece 30' from the cross piece 36. The support 28 may be formed from the extensions 28'-28". Similarly, the guide pin or roller 24 may be supported by ears 24' at the lower end of the blank 32.

In operation the thread is drawn from the cone and fed through suitable guides to the carrier assembly, where it passes the various guides as previously described and is drawn from the discharge tube 17 by the knitting head as the carrier moves across the head. The tension on the yarn lifts the guide rollers 20 and 22, which always tend to fall. At the end of the course, tension is released and guide rollers 20 and 22 fall and take up the slack thus created. It is this very slight backward pull that has necessitated the use of snappers heretofore with their attendant problems of breakage and adjustment.

In case of unsatisfactory action, the guides may be all removed by simply detaching the guide assembly from the carrier assembly and replacing with a previously inspected member. Such an operation causes but a momentary delay in the operation of the machine.

My device is cheap to make, simple in construction, positive in action, easy to install and replace, and requires no adjustment. It can completely do away with the necessary evils inherent in the use of snappers.

I claim:

1. A carrier for a hosiery machine having an introductory guide at one end, a discharge tube at its opposite end, swinging takeup guides, another guide intermediate the takeup guides and the discharge tube, and a single support for all of said guides detachably mounted on said carrier.

2. A yarn takeup device on a hosiery machine carrier comprising in sequence a riser, a hinged takeup guide, a second riser, a second hinged takeup guide and a third riser, said takeup guides exerting an inward pressure on the yarn.

3. In a hosiery machine, a carrier assembly thread takeup device comprising alternating raised guides and hinged takeup guides adapted to swing toward the carrier by gravity.

4. A carrier assembly having an introductory guide at its upper end, a discharge tube at its lower end, a movable takeup device between said ends, said carrier having a groove leading to said discharge tube, and a raised guide on the carrier between said takeup device and said groove.

5. A yarn take-up mechanism for a hosiery knitting machine comprising an inclined carrier arm having an introductory yarn guide at its upper end and a discharge tube at its lower end, a yarn guide projecting outwardly from the carrier arm below said introductory yarn guide for supporting yarn, and a hold-down yarn guide hinged to swing by gravity against the yarn below said projecting guide and take up slack in the yarn above the discharge tube.

6. A yarn take-up mechanism for a hosiery knitting machine comprising an inclined carrier arm having an introductory yarn guide at its upper end and a discharge tube at its lower end, a yarn guide projecting outwardly from the carrier arm below said introductory yarn guide for supporting yarn, a hold-down yarn guide hinged to swing below said projecting guide and means for limiting the outward swinging of said hold-down guide.

7. In a hosiery knitting machine, an inclined carrier having an introductory yarn guide at its upper end and a discharge tube at its lower end, a support projecting outwardly from said carrier, a yarn guide member carried by said support for supporting yarn below the introductory yarn guide, a weighted yarn guide hinged to said support to swing down on the yarn after it passes over the supporting guide member and before it reaches the discharge tube to take up slack in the yarn.

8. In a hosiery machine, an inclined carrier having an introductory yarn guide at its upper end and a discharge tube at its lower end, a transverse yarn guide member for supporting the yarn below the introductory yarn guide, a weighted yarn guide hinged to swing down on the yarn after it passes over the transverse guide member and before it reaches the discharge tube to take up slack in the yarn, and means for limiting the outward swinging of the weighted guide.

9. A carrier assembly attachment comprising a sheet metal strip having an introductory yarn guide at its upper end and a yarn guide at its lower end, a support carried by said strip between its ends, a guide member carried by said support above said strip, a hold-down guide hinged to said support to swing by gravity below said guide member, means for detachably securing said assembly attachment to a carrier, said parts being arranged so that yarn may be led through the introductory guide, thence over the guide member, thence beneath said hold-down guide and thence over said lower guide.

10. A carrier assembly attachment comprising an elongated strip having an introductory yarn guide at its upper end and a guide roller at its lower end, a support carried by said strip between its ends, a guide roller carried by said support, a hold-down guide hinged to said support to swing by gravity below said guide roller, means for detachably securing said assembly attachment to a carrier above the discharge tube thereof, said parts being arranged so that yarn is led from the introductory guide, thence over the guide roller, thence beneath said hold-down guide and thence to the discharge tube.
